UNITED STATES PATENT OFFICE

JOSEPH L. KALLUS, OF BROOKLYN, NEW YORK

DESIGN FOR AN ADVERTISING DOLL

Application filed October 7, 1930. Serial No. 37,178. Term of patent 14 years.

To all whom it may concern:

Be it known that I, JOSEPH L. KALLUS, a citizen of the United States, and resident of the borough of Brooklyn, in the county of Kings, city and State of New York, have invented a new, original, and ornamental Design for Advertising Dolls, of which the following is a specification, reference being had to the accompanying drawing, forming part thereof.

Fig. 1 is a front elevation of a doll showing my new design and Fig. 2 is a side elevation thereof.

The design consists of a doll having a jointed body and limbs, the feet encased in boots and a hat simulating a radio tube.

I claim:

The ornamental design for an advertising doll, as shown and described.

JOS. L. KALLUS.
